Primary Examiner—Jeffrey Asch

(74) Attorney, Agent, or Firm—Banner & Witcoff, Ltd.

(57) **CLAIM**

The ornamental design for a key matrix for a handset, as shown and described.

DESCRIPTION

FIG. 1 is a perspective front view of a key matrix for a handset showing my new design; and,
FIG. 2 is a front view thereof.

The broken line showing of the remainder of the handset is for illustrative purposes only and forms no part of the claimed design.

1 Claim, 2 Drawing Sheets

FIG.1

FIG.2
